DRILL PIPE PROTECTOR AND TOOL
THEREFOR

Emmet S. Long, Los Angeles, Calif.

Application July 5, 1940, Serial No. 344,005

6 Claims. (Cl. 29—88.2)

My invention relates to a drill pipe protector and a tool for use in setting the protector in a desired location upon a length of drill pipe and has particular reference to a pre-expanded resilient protector adapted to be readily installed by means of hand tools.

It is common practice in the oil producing industry to employ drill pipe protectors which are placed at frequent intervals along the length of the drill string for the purpose of preventing the drill string from coming into contact with the walls of the bores as the string is rotated during drilling operations. These protectors usually comprise an annular band of rubber or similar composition having a normal internal diameter less than the external diameter of the pipe, the protectors being stretched or expanded and slipped onto pipe where they are held by the friction developed through their contraction upon the pipe.

Prior to my invention these protectors were shipped to the drilling location in an unstressed condition requiring that they be stretched sufficiently to pass the tool joints in order to permit them to be slipped onto the pipe. These protectors usually have an axial length of from three to four inches or more and a thickness of an inch or more, with the result that enormous expansive forces must be exerted in order to stretch such a protector sufficiently to permit it to pass over a tool joint.

Two methods are in common use today for installing such protectors upon drill pipe. One of these methods includes the use of a tapered mandrel which is secured to the downwardly extending end of a tool joint half. The ring is placed on a suitable support and the small end of the mandrel is inserted within the ring. The pipe and mandrel are then forced downwardly through the ring, causing the ring to expand and pass over the tool joint at which time it contracts and firmly grips the pipe. If a second protector is to be placed on the same string of pipe, it is necessary that a ring clamp or similar device be placed about the pipe between the ring first installed and the tool joint, and the pipe additionally lowered to move the ring to the desired location on the pipe and then the installation of the second ring may be accomplished by the use of the mandrel.

Such an operation is expensive and time consuming and attempts have been made to overcome this disadvantage by supplying the rings in a pre-expanded condition upon a sleeve or short section of pipe having an internal diameter suffi-

cient to pass over a tool joint. With this type of ring the sleeve and the protector ring are slipped along the pipe to the desired position and then a special jack is employed for sliding the ring off of the sleeve and onto the drill pipe. This method of installing drill pipe protectors has not been entirely satisfactory for the reason that the jack mechanism which must be employed is relatively complicated and expensive and requires highly skilled men for its operation.

It is therefore an object of my invention to provide a method of installing drill pipe protectors which consists in holding the protector ring in a pre-expanded condition by means of a sleeve, placing the ring about the drill pipe, and then removing the sleeve from between the ring and the pipe.

It is also an object of my invention to provide a drill pipe protector ring and sleeve for holding the ring in a pre-expanded condition in which the sleeve is composed of two semi-cylindrical portions permitting these portions to be removed from within the protector ring and then taken from the drill pipe without requiring the sleeve to be slipped beyond the end of such drill pipe.

It is an additional object of my invention to provide a protector and sleeve construction of the character set forth in the preceding paragraph wherein the sleeve halves are so arranged that the force required to slip the protector ring from the sleeve may be obtained from the highly stretched condition of the protector ring itself.

It is a still further object of my invention to provide a protector ring and sleeve construction of the character set forth hereinbefore in which the sleeve halves may each be pivotally moved relative to each other about an axis extending transversely of the axis of the drill pipe to change the sleeve shape from cylindrical to conical, whereby the forces derived from the highly stretched condition of the ring operate to slip the ring toward the small diameter end of the conical sleeve.

It is an additional object of my invention to provide a tool for use with a protector ring and sleeve construction of the character set forth in the preceding paragraphs.

It is also an object of my invention to provide a tool of the character mentioned in the preceding paragraph which includes a means for engaging the sleeve halves of a protector ring and sleeve construction of the character set forth hereinbefore and which also includes a handle means, whereby the sleeve halves may be pivotally moved

from a position defining a cylindrical surface to a position defining a conical surface.

Other objects and advantages of my invention will be apparent from a study of the following specifications, read in connection with the accompanying drawing, wherein:

Fig. 1 is a fragmentary elevational view with parts shown in section illustrating the manner in which one form of tool of my invention may be employed for installing a protector ring constructed in accordance with my invention upon a section of drill pipe which is illustrated in Fig. 1 as being held by slips inserted in a rotary table of the type commonly employed on oil well drilling equipment;

Fig. 2 is a perspective view illustrating the construction and appearance of the protector ring of my invention and the split sleeve upon which the ring is supplied in a pre-expanded condition;

Fig. 3 is a perspective view of one of a pair of identical tools which may be employed for the purpose of slipping the protector ring from the sleeve and onto the drill pipe;

Fig. 4 is an enlarged view with parts shown in section illustrating the manner in which the engagement between the tools and the sleeve portions is obtained;

Fig. 5 is a view similar to Fig. 4 illustrating the positions occupied by the parts at the beginning of an installing operation;

Fig. 6 is a view similar to Figs. 4 and 5 but illustrating the relative positions of the parts at the time the resilient protector ring is slipped from the sleeve members upon which it is carried; and

Fig. 7 is a fragmentary horizontal section illustrating the details of construction of a locking mechanism which may be employed to lock the tools of my invention to the sleeve members forming a part of the protector ring assembly.

Referring to the drawing, I have illustrated diagrammatically in Fig. 1 a rotary table as comprising a flat table-like member 1 within which is inserted slips 2 for the purpose of gripping and supporting a section of drill pipe 3. I have indicated at 4 a drill pipe protector 5 which is illustrated as resting upon the slips 2 preparatory to installation thereof at that point. I have also illustrated in Fig. 1 an annular clamp 6 which is secured to the drill pipe 3 at a point spaced above the rotary table 1 and have indicated another of the drill pipe protectors 5 as resting upon the clamp 6 preparatory to installation at that point along the length of the length of drill pipe 3. Fig. 1 also illustrates the appearance of setting tools 7 which may be employed for effecting the installation of the protector ring.

Referring to Fig. 2, I have illustrated the preferred embodiment of the protector ring 5 of my invention as comprising a hollow rubber cylinder having a length of from four to seven inches, a wall thickness of an inch or more and a normal internal diameter somewhat less than the outside diameter of the drill pipe 3. The protector ring 5 is illustrated in Fig. 2 as being pre-expanded and held in such expanded condition by means of a sleeve 8 which is formed of coacting sleeve halves 9 and 10. These sleeve halves are each preferably semi-cylindrical in form and include upper and lower marginal portions 11 and 12 extending above and below the protector ring 5. Each of the sleeve halves abut each other along axially extending surfaces 13, which abutting surfaces extend downwardly from the

upper marginal portions 11 to a point somewhat below the center of the protector ring 5. At this point each surface is inclined outwardly as indicated at 14, the junction between the surfaces 13 and 14 defining a fulcrum or heel 15. The inside diameter of the sleeve 8 is preferably made sufficiently large to permit it to pass over a tool joint so as to permit the protector rings 5 to be slipped over the end of a length of drill pipe and be moved axially therealong to any desired position.

I have illustrated in Fig. 3 the appearance and construction of the preferred embodiment of the tool of my invention which preferably includes a semi-cylindrical portion 16 having inside and outside diameters substantially conforming to the outside diameter of the drill string 3 and the inside diameter of the sleeve 8, respectively. The upper end of the semi-cylindrical portion 16 may carry a handle bracket 17 which defines a radially outwardly extending surface 18 having a width substantially equal to the thickness of each of the sleeve halves 9 and 10. The handle bracket 17 may also carry a curved tailpiece 19 which extends downwardly from the location of the radial surface 18 and to which may be affixed a handle member 20.

When the drill pipe protector and its sleeve 8 is slipped on the drill pipe 3 to its desired location, it may be held in such position either by the rotary table 1 or by the aforementioned split clamping ring 6. In either event after the desired position of the protector ring 5 is established, the tools 7 are placed in position somewhat in the manner illustrated in Fig. 4. It will be noted that the semi-cylindrical portion 16 of the tool is inserted between a sleeve 8 and the drill pipe 3 and that the radially extending surface 18 serves as a stop by engaging the upper edge of the sleeve member 8. Similarly, the downwardly extending tailpiece 19 extends downwardly along the outside of the upper marginal portions 11 of the sleeve 8, whereby the sleeve halves are each secured to the handles of the tools 7 to permit outward and downward movement of these handles to tend to pivot each of the sleeve halves about an axis extending substantially horizontally.

It will be noted that such outward and downward force applied to the handle 20 will cause the sleeve halves 9 and 10 to be pivotally moved relative to each other about the fulcrum or heel portion 15 so as to bring the inclined surfaces 14 into abutting relationship with each other and to separate the axially extending surfaces 13. When this condition obtains the parts are disposed in a position such as that illustrated in Fig. 5 and attention is called to the fact that downward movement of the protector 5 relative to the drill pipe 3 is prevented during this operation by engagement of the lower marginal portion 12 of the sleeve 8 with either the split clamping ring 6 or the upper surface of the slips 2 in the rotary table. Attention is also called to the fact that the lower marginal portions 12 of the sleeve halves 9 and 10 are preferably relieved as indicated at 21 so as to permit these portions to be moved inwardly by the aforementioned pivotal action without being brought into engagement with the drill pipe.

The angularity of the inclined surface 14 relative to the axial surfaces 13 is preferably so adjusted that when the parts are moved to the position illustrated in Fig. 5 the angle of the quasiconical surface thus produced is sufficiently

steep to bring the protector ring to the verge of slipping lengthwise along such inclined or tapered surface. It will be appreciated that a relatively small additional force will then cause the protector ring 5 to move axially relative to the sleeve halves 9 and 10. This slight additional force may be obtained by exerting an additional downward and outward pull on the handle members 20 so as to cause the angularity of the sleeve halves 9 and 10 to increase slightly as is indicated in Fig. 6. When this is done the large compressive force which is exerted by the protector ring 5 serves to move the sleeve halves 9 and 10 upwardly and out from between the protector ring and the drill pipe with the result that the protector ring immediately shrinks upon the drill pipe 3 and is secured thereto.

In view of the fact that such protector rings may be installed at a considerable height above the derrick floor, it is highly desirable that some means be provided to prevent the falling of either of the sleeve halves 9 and 10 to the derrick floor at the time the protector ring 5 is installed. I therefore provide in the upper marginal portion 12 of each of the sleeve halves 9 and 10 a small aperture 22 which is adapted to be engaged by a pin 23 carried by each of the tools 7 so as to lock each sleeve half to the tool with which it is associated. The pin 23 is preferably mounted for slidable movement in bores extending radially through the tailpiece 19 and the semi-cylindrical portion 16 so that after the tool is placed in the position illustrated in Fig. 4 relative to one of the sleeve halves, the pin will be engaged with the sleeve half and both of the members 16 and 19 of the tool.

Ready retraction of the pin may be obtained by employing a construction such as that illustrated in Fig. 7 wherein the outer end of the pin 23 is pivotally secured as by means of a pin 24 to a lever 25 which is in turn mounted for pivotal movement as by a pivot 26 carried on the tailpiece 19. The lever 25 is preferably spring urged to a position placing the pin 23 in its innermost position as by interposing a compression spring 27 between the tailpiece 19 and the outermost end of the lever 25. It will be observed that with this construction the pin 23 may be retracted by merely pressing the lever 25 toward the tailpiece 19 and that release of such pressure will permit the spring 27 to move the pin 23 to its innermost position.

The holes 22 may also be employed for preventing accidental shifting of the protector ring 5 from the sleeve halves 9 and 10 during shipment by disposing the holes 22 in diametrically opposite positions relative to each other and by passing a bolt or other suitable locking member through these holes.

In order for the above described operation of moving the sleeve halves 9 and 10 pivotally relative to each other, it is necessary to maintain the abutting edges 13 in alignment with each other by preventing either of the sleeve halves from moving laterally relative to the other. The holding of the sleeve halves against such undesired lateral movement may be readily accomplished by making each of the semi-cylindrical portions 16 of the tools 7 embrace somewhat more than a half circle. The required overlap between the tools when they are both inserted between the sleeve halves 9 and 10 and the drill pipe 3 in the manner illustrated in Fig. 4 may be accomplished by beveling longitudinally extending ends of one

of the semi-cylindrical portions 16 internally as indicated at 28 in Fig. 3 and by providing a corresponding external bevel on the edges of the semi-cylindrical portion of the other tool member 7. With the tools constructed in this fashion they will overlap each other in the manner indicated in Fig. 4 when they are placed between the sleeve halves and the drill pipe.

Reference to Fig. 4 will indicate that the semi-cylindrical portion 16 of one of the tools 7a is illustrated as carried beyond the abutting edge surface 13 as indicated by the solid line 29, whereas, the corresponding edge 30 of the other tool 7b is indicated by means of the dotted line 30 as being disposed on the inside of the portion 16 of the tool 7a and extended beyond the abutting edge surfaces 13 in the opposite direction. It will be appreciated that by thus causing the semi-cylindrical portion 16 of each of the tools to extend beyond the abutting edge surfaces 13, lateral movement of one of the sleeve halves 9 or 10 relative to the other will be positively prevented.

From the foregoing it will be observed that I have provided a drill pipe protector ring which is adapted to be supplied to those desiring to install protector rings on drill pipe in a preexpanded condition and that the sleeve which is employed to maintain the ring in such pre-expanded condition is so constructed as to permit the ring to be readily removed from such sleeve.

It will also be observed from the foregoing that I have provided a hand tool which may be employed with the protector ring construction of my invention for permitting the rings to be installed at any desired location along a length of drill pipe and that through use of the ring and tool construction of my invention protector rings may be installed on drill pipe at any desired location without requiring specially trained or skilled labor for such installation.

While I have shown and described the preferred embodiment of my invention, I do not desire to be limited to any of the details of construction shown or described herein, except as defined in the appended claims.

I claim:

1. In a sleeve construction for insertion into a hollow cylindrical rubber drill pipe protector having an inside diameter normally less than the outside diameter of said drill pipe to hold said protector in an expanded condition, a pair of complementary semi-cylindrical sleeve halves to be disposed in abutting relation to each other to form a complete cylindrical sleeve having an inside diameter greater than the outside diameter of said drill pipe, the meeting edge faces of said sleeve halves extending axially for a part of the length of said sleeve to constitute coacting abutment faces and extending angularly away from each other the remaining part of the length of said sleeve.

2. In a sleeve construction for insertion into a hollow cylindrical rubber drill pipe protector having an inside diameter normally less than the outside diameter of said drill pipe to hold said protector in an expanded condition, a pair of complementary semi-cylindrical sleeve halves to be disposed in abutting relation to each other to form a complete cylindrical sleeve having an inside diameter greater than the outside diameter of said drill pipe, the meeting edge faces of said sleeve halves extending axially for a part of the length of said sleeve to constitute coacting abutment faces and extending angularly away from each other the remaining part of the length of

said sleeve, said edge faces being smoothly curved outwardly at the junction of the angularly extending parts to define coating fulcrums about which said sleeve halves may be pivotally moved.

3. In a sleeve construction for insertion into a hollow cylindrical rubber drill pipe protector having an inside diameter normally less than the outside diameter of said drill pipe to hold said protector in an expanded condition, a pair of complementary semi-cylindrical sleeve halves to be disposed in abutting relation to each other to form a complete cylindrical sleeve having an inside diameter greater than the outside diameter of said drill pipe, the meeting edge faces of said sleeve halves extending axially for a part of the length of said sleeve to constitute coating abutment faces and extending angularly away from each other the remaining part of the length of said sleeve, said edge faces being smoothly curved outwardly at the junction of the angularly extending parts to define coating fulcrums about which said sleeve halves may be pivotally moved relative to each other to bring said angularly extending parts into abutting relation with each other and change the shape of said sleeve from cylindrical to quasi-conical, said angularly extending parts being disposed at such angle as to cause the angularity of the quasi-conical surface to be less than that required to cause said ring to slip axially along said sleeve.

4. In a sleeve construction for insertion into a hollow cylindrical rubber drill pipe protector having an inside diameter normally less than the outside diameter of said drill pipe to hold said protector in an expanded condition, a pair of complementary semi-cylindrical sleeve halves to be disposed in abutting relation to each other to form a complete cylindrical sleeve having an inside diameter greater than the outside diameter of said drill pipe, the meeting edge faces of said sleeve halves extending axially for a part of the length of said sleeve to constitute coating abutment faces and extending angularly away from each other the remaining part of the length of said sleeve, said edge faces being smoothly curved outwardly at the junction of the angularly extending parts to define coating fulcrums about which said sleeve halves may be pivotally moved, whereby a pair of tool means each including a member insertable between one of said sleeve halves and said drill pipe and having a portion engageable with the end of said sleeve half may be employed to move one end of each of said halves pivotally outward from said drill pipe

about said fulcrum to slide said rubber cylinder from said sleeve.

5. In a sleeve construction for insertion into a hollow cylindrical rubber drill pipe protector having an inside diameter normally less than the outside diameter of said drill pipe to hold said protector in an expanded condition, a pair of complementary semi-cylindrical sleeve halves to be disposed in abutting relation to each other to form a complete cylindrical sleeve having an inside diameter greater than the outside diameter of said drill pipe, the meeting edge faces of said sleeve halves extending axially for a part of the length of said sleeve to constitute coating abutment faces and extending angularly away from each other the remaining part of the length of said sleeve, said edge faces being smoothly curved outwardly at the junction of the angularly extending parts to define coating fulcrums about which said sleeve halves may be pivotally moved, whereby a pair of tool means each including a member insertable between one of said sleeve halves and said drill pipe and having a portion engageable with the end of said sleeve half may be employed to move one end of each of said halves pivotally outward from said drill pipe about said fulcrum to slide said rubber cylinder from said sleeve, each of said sleeve halves including means for cooperating with a locking means on

30 each of said tool means for locking each of said halves to its associated tool means.

6. In a tool for removing from within a pre-expanded drill pipe protector a holding sleeve consisting of a pair of sleeve halves of semi-cylindrical form disposed in abutting relation to each other along axially extending side edges and defining a sleeve having an inside diameter greater than the outside diameter of said drill pipe, a pair of semi-cylindrical members each 35 insertable between one of said sleeve halves and said drill pipe and each having a portion engageable with the end of said sleeve half, whereby one end of each of said halves may be moved pivotally outward from said drill pipe to slide 40 said rubber cylinder from said sleeve, each of said semi-cylindrical members having a circumferential scope sufficient to extend more than half way around the interior of said sleeve and terminating in axially disposed edge porcions, 45 said edge portions of said members being oppositely beveled so as to lie in overlapping relation with each other when both of said members are inserted between their respective sleeve halves and said drill pipe.

EMMET S. LONG.
